CLAIM

The ornamental design for a double onigiri package, as shown and described.

DESCRIPTION

FIG. 1 is a top perspective view of the present invention; FIG. 2 is a front plan view thereof;

FIG. 3 is a rear plan view thereof;

FIG. 4 is a left-side plan view thereof;

FIG. 5 is a right-side plan view thereof;

FIG. 6 is a top plan view thereof;

FIG. 7 is a bottom plan view thereof;

FIG. 8 is a bottom perspective view thereof; and,

FIG. 9 is a bottom perspective view thereof, shown with environment.

The broken lines shown bisecting the package represent a perforation line. All additional broken lines shown in FIG. 9 are for the purpose of illustrating environmental structure and form no part of the claimed design.
